UNITED STATES PATENT OFFICE.

HENRY HADIDA, OF LONDON, ENGLAND.

STAMP-AFFIXING APPARATUS.

No. 863,169.

Specification of Letters Patent.

Patented Aug. 13, 1907.

Application filed March 3, 1906. Serial No. 304,102.

To all whom it may concern:

Be it known that I, HENRY HADIDA, a subject of the King of England, residing at 24 Rood Lane, in the city and county of London, England, merchant, have invented certain new and useful Improvements in Stamp-Affixing Apparatus, of which the following is a full, clear, and exact description, reference being made therein to the accompanying drawings.

This invention relates to an improved apparatus for affixing stamps, labels and the like to envelops, certificates, lace, piece-goods and the like.

It consists of a machine which is supplied with perforated strips of stamps or labels, the stamps being detached, moistened on the underside and applied to the letter or other surface as the result of a single blow upon a plunger.

A machine made according to the present invention is also characterized by being compact, self-contained and of simple construction; by the stamp being delivered and impressed by the same device which cuts it from the strip and at the same operation as the latter; by the construction and operation of the device for moistening the underside of the stamp or label; and by the disengageable device for feeding forward the stamp strip.

The invention is described with reference to the accompanying drawings in which:

Figure 1 is a side elevation and Fig. 2 is a plan of a machine for affixing ordinary postage stamps to letters. Fig. 3 is a sectional elevation. Fig. 4 is a front view at right angles to Fig. 1 but showing a portion of the casing removed. Figs. 5 and 6 are detail views of the ratchet wheel and of the catch or locking device. Fig. 7 is a vertical sectional view showing the thumb piece *h* and its lever arm.

The stamps *a* are wound in a single strip or in connected continuous strips around a drum *d* revolvably mounted in suitable bearings *c* upon the machine. The stamps when actually being fed forward have their gummed side underneath. If desired, a brake (not shown) may be applied to the spindle or other convenient portion of the drum so as to retard the unwinding of the latter. From this drum the strip *a* is carried to a feed roller *d* secured on a spindle *d'*. This roller is provided with a milled periphery *d''* and the strip *a* is maintained against the latter by any suitable device. In the drawings a second roller *e* is shown for this purpose mounted at one end of a plate *f* which is at its other end pivoted to the machine at *f'*. A plate spring *g* acts upon the underside of this pivoted plate *f* to hold the roller *e* normally against the roller *d* and this spring *g* may be depressed by means of a thumb-piece *h*. The latter is shown arranged transversely of the machine and secured at one end to an arm *h'* which may at its other end be pivoted at *h''* to the casing of the machine or be formed as a spring arm secured thereto. The arrangement in either case is such that when the thumb piece *h* is operated, the spring *g* is held down and the pivoted plate *f* falls by its own weight so that the roller *e* is no longer pressed against the roller *d*.

The upper side of the plate *f* acts as a feed plate or track for the strip *a* and is continued almost up to the knife edge or blade *i* which is arranged across the path of the strip *a*. This blade is located to one side of a plunger barrel *j* and the foremost stamp projects over the blade *i* and remains immediately above or even rests upon the inner ends of two pivoted levers *p p*, forming a moistening device. It will be thus seen that if the thumb piece be depressed the strip of stamps *a* can be moved freely upon the plate *f* so that the position of the perforated line between the first and second stamp can be fixed with certainty at any time.

The plunger preferably consists of a tube *k* and stem *l* with a helical spring *j'* interposed and the plunger is movable vertically in the barrel *j*. Spring *j'* serves to return the plunger after its descent, being compressed between the knob head *y* and the cross stud *o*. The plunger may be of any convenient shape and appearance, but is shown on the drawings as of tubular rectangular section. The lowermost part of the plunger stem *l* is enlarged to form an abutment *m* for a second spring *j*; the end or head *n* is fitted with one or more pins, needle points or the like *n'*. Both these inner and outer parts *k l*, are slotted, as shown at *k' l'* in Figs. 3 and 4, and the outer one to a greater length than the inner one. A stud *o* projects into these slots *k' l'* from the barrel, and the pin *n'* shown may pass through either a cut-away part or a perforation in a plug or stop-piece fitted in the bottom of the outer part *k*. The inner spring *j* bears upon the shoulder formed on stem *l* its upper end being confined by the shank *y* of the knob head *y*, so as to keep the pin head *n n'* extended to move with the part *k* until the stud *o* is struck by the extremity of the slot *l'*.

The pivoted levers *p* are provided at their outer ends with reservoirs or wells *p'* for water so that the inner ends, provided with felt pads, brushes or the like *q q* may be kept constantly moistened. Communication exists between the pad and the well by a passage or other arrangement, and if preferred the pad may be kept moistened by means of capillary attraction. These levers may be hollow therefore and they are pivoted freely in the sides of the barrel *j*, their inner ends *q* standing in the path of the plunger. If the stamps are not already gummed, the pads *q* may, instead of applying water to a gummed surface, actually supply the necessary adhesive material such as gum to the underside of the stamp.

Upon the spindle *d'* and so as to rotate step by step with the roller *d* are secured a ratchet wheel *r* and a notched wheel *s*. The wheel *r* is fitted with teeth of such a length that the advance of this wheel *r* to the extent of one tooth will result in the strip *a* being fed for-

ward to the extent of the length of one stamp. Wheel *r* is operated by a pawl *t* linked or otherwise connected to the plunger so as to be operated by the upward movement of the latter. The connection between the pawl 5 *t* and the plunger may be carried out in any convenient manner, the form shown being by means of the rod *t'* which is held away from the barrel (so that *t* will engage the ratchet teeth as it rises) by a small plunger *x''* pressed outwardly by a spring *x'*. In Fig. 5 the pawl *t* has just 10 lifted the ratchet tooth.

The notched wheel *s* is locked by means of a pawl or projection *u'* backed by a spring-pressed bar *u* which normally holds the wheel *s* and therefore the roller *d* stationary. By means of a pawl *v* operating during the 15 rise of the plunger the bar *u* is lifted and the catch *u'* withdrawn from the particular notch in the wheel and this action takes place immediately before the pawl *t* operates to rotate the wheel *r*. The plunger *k* lifts the extremity of the bar *u* by means of the pawl *v*, as stated, 20 and this pawl is also pressed outwardly by a small plunger *x* and the spring *x'*, see Fig. 6.

On the downward stroke of the plunger *k* the pawls *t v* of course ride over the wheel *r* and the extremity of bar *u* respectively.

25 Below the moistening levers *p* the barrel is cut away to allow of the insertion of the envelop in the desired position below and immediately in the path of the plunger, and if desired, a flat base or table may be provided, as shown, to afford stability to the apparatus.

30 As the plunger is depressed both the lower parts descend and bear upon the stamp which is projecting over the knife edge *i*. The stamp is pierced by the pin *n'* and then sheared off at its perforated line over the edge *i*, the loose stamp remaining impaled upon 35 the pin. The continued downward movement of the plunger presses the stamp upon the pads *q* pushing aside the facing ends of the levers *p*. By this means it is insured that the underside of the stamp is dampened. The completion of the descent of the plunger 40 applies the moistened stamp to the envelop inserted upon the table at the base of the barrel. Owing, however, to the difference in lengths of the slots *k' l'* formed in the lower half of the plunger, the extremity of the slot in the pin-headed part meets the limiting 45 stud *o* before the lower half of the plunger reaches the envelop. There is therefore no risk of the pin entering the envelop because the pin *n'* is withdrawn to some slight extent into the outer or bottom part of the lower half of the plunger. The stamp is removed from 50 the pin and continued in its downward movement by the part of the plunger which is fitted with the longer slot and detaches the stamp from the pin.

The use of the pin (or pins) *n'* is advantageous since it holds the stamp firmly and prevents it from escaping 55 during the downward movement of the plunger.

As the plunger returns upwardly, being so impelled by the spring or springs *j'*, the wheel *r* is rotated by pawl *t* and another stamp pushed over the blade *i*. The levers *p* face one another again at their inner ends 60 and if so arranged support the stamp *a*. The feeding forward of the strip unwinds the drum and this movement of the latter may, as stated be restricted to the necessary amount by the brake before mentioned.

A pad *w* of some comparatively soft material such as 65 rubber or leather may be provided in the base of the

machine below the plunger to act as a cushioning device for the latter.

The apparatus may be applied to other purposes in which a stamp, label or the like is to be affixed to a surface such as in the case of certificates, strips of materials, samples of soft goods and the like. 70

Instead of the strip *a* being perforated it may consist of a continuous strip having merely printed thereon the desired stamps, labels or the like without intermediate perforations. 75

The stem *l* is suitably guided within the cylinder *k*. In the accompanying drawings, (see Fig. 3) I have shown the socket *k* provided with a knob head *y* screwed thereto and this head is furnished with a central guide 80 for the stem *l*.

Having thus described my invention what I claim as such and desire to secure by Letters Patent is:—

1. A stamp-affixing apparatus comprising a depressible hollow plunger, a barrel in which said plunger is arranged to travel reciprocally, springs within said hollow plunger, 85 a drum upon which a strip of stamps is wound, a feed roller operated by the return movement of the plunger, said feed roller having a milled periphery so as to grip said strip, a pressure roller adapted to hold said stamp strip against said feed roller and a fixed blade mounted in said guide barrel and over which said strip is fed. 90

2. A stamp-affixing machine comprising a reciprocable plunger, a casing, a fixed blade, means for feeding a stamp strip forward over said fixed blade so that the foremost stamp is in the path of the plunger and a double armed moistening device fulcrumed on the exterior of the casing and having one lever arm in the path of the plunger below said stamp and the other arm forming a reservoir and balance weight, the inner arm of said moistening device being displaceable laterally to allow the moistened stamp 100 to be impressed by the plunger. 95

3. A stamp-affixing machine comprising a tubular plunger, a spring concealed within said plunger, a guide for said plunger, a device for feeding forward a strip of labels, a blade fixed in the guide and over which said labels are fed, a displaceable moistening pad situated below said blade mounted on a lever fulcrumed intermediate of its length and balanced by a water reservoir, and an operative device for shearing the label over said blade pressing it upon the pad and applying it at the same stroke to its 110 intended surface. 105

4. A stamp-affixing machine comprising means for automatically feeding forward a strip of stamps, means for detaching the foremost stamp and moistening its underside, an impaling device for holding the stamp in position and means for detaching said stamp from said impaling device and affixing it to the surface which is to bear it, the whole of these operations being performed by a single forward and return stroke of an operating device. 115

5. A stamp-affixing apparatus comprising a plunger device secured to and reciprocable in said apparatus, means for impaling a stamp, said means being carried by said plunger device, and means operating on the downward movement of the plunger device for detaching the impaled stamp from its transfixing device. 120

6. A stamp-affixing apparatus comprising a base, a barrel secured upon said base, the lower part of said barrel being cut away laterally to allow of the insertion of the surface on which the stamp is to be impressed, a cushioning pad upon said base immediately below said barrel, a plunger reciprocable in said barrel, and means for feeding forward a strip of stamps over a blade, the foremost of said stamps being sheared and impressed by the downward stroke of said plunger and means for guiding said stamp during its downward movement said means consisting of an impaling pin carried by the plunger. 130

7. A stamp-affixing apparatus comprising a base, a casing mounted on said base, a barrel secured upon said base and having its lower part cut away laterally, a plunger reciprocable in said barrel and provided with means for 140 shearing a stamp and engaging such sheared stamp, a revo-

- luble drum upon which the stamps or labels are wound in a strip, said drum being mounted on an axle and said axle being removably seated in slotted supports in said casing, a feed roller having a milled periphery and adapted to be rotated to a predetermined extent by the movement of the plunger, a plate track for the stamp-strip leading such strip from the said drum to said feed roller, said track being pivoted at one end and spring supported at the other end, a pressure roller mounted on said plate track and held by a spring against said feed roller, and a blade over which said strip is fed, said blade being arranged in prolongation of said track.
8. A stamp-affixing apparatus comprising means for feeding forward a strip of stamps, a plunger secured in a barrel mounted on said apparatus, a spring concealed within said plunger, a moistening device comprising double arm levers, the inner ends of which project into the path of said plunger, and a table at the foot of said barrel upon which the surface for the stamp is laid, said table being fitted with a cushioning device and said plunger displacing the moistening device sidewise after having pressed the stamp thereon.
9. In a stamp affixing apparatus, a plunger comprising a stem and a cylinder, said stem being guided in said cylinder, a perforated base to said cylinder, a pin upon the lower end of said stem projecting through said perforated base, a barrel for said plunger mounted on said apparatus, slots in said stem and cylinder, the slot in said cylinder being longer than the slots in said stem, a cross piece secured in the plunger cylinder and projecting through said slots and serving towards the end of the depression stroke of the plunger to withdraw said pin into said cylinder.
10. A stamp affixing apparatus comprising a depressible plunger of uniform width, a barrel for guiding said plunger and extending over the greater portion of the length of said plunger, a blade over which a strip of stamps is fed, a lever pivoted intermediate of its length upon the apparatus having one end projecting into the barrel, said lever containing liquid and having an absorbent surface secured upon the inner arm of the lever, the outer portion of said lever acting as a reservoir, said lever being adapted to be tilted by the downward stroke of the plunger so that the reservoir then feeds the inner end of the lever.
11. In a stamp-affixing machine, a plunger adapted to reciprocate in a cylindrical guideway, hollow lever arms pivoted intermediate of their length upon the guideway with their inner ends normally facing one another, said inner arms being in the path of the plunger so as to be displaced by the downward stroke of said plunger, said levers containing fluid to moisten and render adhesive the underside of the stamp and being selfrighting by gravitation after the plunger has returned.
- 55 12. In a stamp affixing apparatus, a feed roller having a milled periphery, means for intermittently rotating said feed roller, a pivoted track, a smooth surfaced roller secured upon the free end of said track, said smooth roller being held against said feed roller by a spring arm.
13. In a stamp affixing machine, a reciprocable plunger, 60 a feed roller having a milled periphery, an axle for said roller, a notched wheel mounted on said axle, a ratchet wheel also mounted on said axle, a pawl engaging said ratchet wheel, a locking device engaging said notched wheel, both pawl and locking device being operated by the aforementioned plunger, a double-armed moistening device fulcrumed intermediate of its length and also operated by said lever so as to be displaced laterally after having moistened the underside of the stamp.
14. A stamp affixing apparatus which comprises a reciprocating plunger device, means for automatically feeding forward a strip of stamps, a yielding plate track pivoted at one end and at the other carrying a roller which forms part of said feed device, a pawl and ratchet mechanism for the operation of a feed roller, a locking 75 device for the latter, a trip device secured on the plunger which upon the return stroke disconnects and releases the said locking device, and a spring pushed link carrying the said pawl and operating immediately after such action of the trip device.
15. In a stamp affixing machine, a track pivoted at one end to the machine, a pressure roller mounted at the free end of the track, a feed roller mounted on the machine and against which said pressure roller bears, a spring arm supporting said track intermediate of its 80 length, and a lever pivoted upon the machine and adapted to hold said spring arm away from the track.
16. In a stamp affixing machine, a plunger, pawls linked thereto, spring controlled means for actuating said pawls, and a roller having ratchet teeth thereon actuated and controlled by said pawls for feeding forward to an exact extent a strip of stamps.
17. A stamp affixing machine comprising a base, a barrel supported vertically upon said base, a cut away portion to said barrel, a cushioning pad upon said base below said barrel, a plunger reciprocating in said barrel, a blade fixed in the wall of said barrel, means for feeding forward a strip of stamps over said blade, lever arms pivoted upon said machine and having their inner ends arranged normally to face one another in said barrel said inner ends having 95 moistening pads, a head to said plunger, a pin upon said head in prolongation thereof, said pin being capable of receding into said plunger, and means for actuating the stamp feed operated by the return stroke of said plunger.
- In testimony whereof I affix my signature in presence of two witnesses.
- HENRY HADIDA.
